UNITED STATES PATENT OFFICE

HAROLD A. SNOW AND WILLIAM D. LOUGHLIN, OF BOONTON, NEW JERSEY, ASSIGNEES
TO RADIO FREQUENCY LABORATORIES, INC., OF BOONTON, NEW JERSEY, A CORPO-
RATION OF NEW JERSEY

INPUT COLLECTOR SYSTEM FOR ELECTRICAL AMPLIFIERS

Application filed September 6, 1928. Serial No. 304,276.

This invention relates to electrical amplifier circuits, and more especially to an improved input and collector system for such amplifier circuits, and constitutes an improvement on the input system described and claimed in the copending application of Frederick H. Drake and William D. Loughlin, Serial No. 285,886, filed June 16, 1928. It is particularly applicable to an input and collector system for a radio frequency amplifier suitable for use in radio receiving sets, and the invention will hereafter be described in connection with such an amplifier, in which connection it has many advantages.

An object of the invention is to provide such an input system including an electromagnetic collecting device or loop, and an optional connection to a supplementary electrostatic collecting device or antenna. A further object is to combine such a collector system with an input system constituting a desirable means for coupling said collecting devices to a radio frequency amplifier with which the system is associated. A further object is to provide such an input-collector system including a volume control. Other objects of the invention will appear from the following description:

In the accompanying drawings, the single figure shows a multi-stage radio frequency amplifier including an input and collector system according to the present invention.

Referring now to the drawings, the multi-stage radio frequency amplifier comprises the four vacuum or audion tubes T_1 , T_2 , T_3 , and T_4 , working into detector tube T_5 . Each of the amplifier tubes is provided with an anode or plate P , a grid or control electrode G , and an electron-emitting cathode or filament F . The latter may be heated either by direct or alternating current, and is here shown as being of the alternating current type by way of example. They are supplied from any suitable alternating current source, and may for example be provided with centre tap resistance R_o , by-passed to ground at each end by by-pass condensers C' . A biasing resistance R' may also be employed in order to impart the desired bias to the grids

G. The detector tube T_5 is provided with a plate P and grid G , but, by way of example, is shown as having a cathode composed of an electron-emitting element F , and a separate heater element H , heated by alternating current. The several tubes are linked or coupled together in this multi-stage arrangement by means of a balanced network comprising transformer primary coils L_1 , secondary coils L_2 , zero-coupled balance coils L_3 , balance condensers C_3 , and tuning condensers C_2 , as described and claimed in United States Patent No. 1,672,811 to Lewis M. Hull. The tuning condensers C_2 are suitably arranged as units of a gang, and are tuned together by a common control. The detector tube T_5 is provided with a grid condenser C_g and a leak resistance R_g . Its plate circuit includes the large condenser C' and choke coil or audio transformer primary L . It may operate into a suitable audio frequency amplifier or reproducing device, as desired.

The foregoing radio frequency amplifier and detector system is described by way of example of one form of system in connection with which the input-collector system according to the present invention has been found to give excellent results. The radio frequency amplifier does not per se constitute a part of the present invention, although it does enter into the present invention as an element of a combination. Other radio frequency amplifier systems may, of course, be employed in combination with an input-collector system according to the present invention.

The input-collector system comprises a series circuit including a relatively large fixed coupling condenser C_m , a variable or trimming inductance L_o , an electromagnetic collecting device L_a , ordinarily in the form of a loop or similar arrangement, and a tuning condenser C_o . The junction of the fixed coupling condenser C_m and the tuning condenser C_o is at ground. The terminal A is located between the coupling condenser C_m and the trimming inductance L_o , and is adapted to have an electrostatic collecting device or antenna connected thereto, as indicated, as by means of switch S , in certain

cases. Thus the collecting system always includes the electromagnetic collecting device or loop L_a , which is permanently connected in series in the input circuit, and may also include a supplementary electrostatic collector or antenna connected to the terminal A, in cases where sufficient signal energy is not picked up by the device L_a .

An electromagnetic collector or loop is in many respects a desideratum from a practical viewpoint, since, for example, it may be built into the receiver cabinet, and thus results in a complete and compact unit. There are also certain electrical advantages inherent in this form of collector, e. g. its directional characteristics. In certain locations, however, such for example as the interior of a steel building, the loop fails to function satisfactorily and it becomes desirable to augment the collector structure.

While these facts have been recognized in a general way in the art, the hitherto employed methods of providing for this change have comprised either an actual manual substitution of input systems or elaborate switching schemes for making this change. Such arrangements are unsatisfactory in that they are costly, cumbersome, and unless carefully designed may lower the performance of the receiver.

The input-collector system according to the present invention provides for a self-contained collecting system within the receiver cabinet and a simple means for augmenting the collecting system when local conditions demand it.

A volume control is provided, according to the present invention, by the potentiometer, R, connected across the tuning condenser C_o , and provided with a variable tap, 1, connected to the grid, G, of the first tube, T_1 . Since this potentiometer is connected between the high side of the tuning condenser C_o and ground, it affords a means for applying any desired portion, from zero up to the maximum, of the potential E_o across the input tuning condenser between the grid and cathode of the first tube, T_1 , of the radio frequency amplifier. It therefore furnishes an ideal volume control, is available whether the collector L_a is used alone or in conjunction with the external antenna, and is free from the objections usually accompanying volume controls applied to alternating current tubes.

We have found that the following constants for an input-collector system according to the present invention give very satisfactory results, although they are merely given by way of example, and may be considerably varied.

$$L_a = 135 \mu \text{ henries}$$

$$L_o = 90 \mu \text{ henries min.}; 230 \mu \text{ henries max.}$$

$$C_m = 1000 \mu\mu \text{ farads}$$

$$C_o = 400 \mu\mu \text{ farads (max.)}$$

$$R = 200000 \text{ ohms}$$

With regard to the behavior of this input-collector system as a coupling to a radio frequency amplifier, and as one tuned circuit of such an amplifier, it will be observed that the total tuning capacity of the input system, with the antenna removed, is:

$$C_t = \frac{C_o \cdot C_m}{C_o + C_m} = \frac{C_o}{1 + \frac{C_o}{C_m}}$$

75

The antenna capacity, when the antenna or electrostatic collector is employed, is effectively in parallel with C_m and acts to increase the effective value of C_m in the above equation.

If C_m is large compared with C_o , as is the case when the circuit is tuned to short wave lengths, the term $1 + \frac{C_o}{C_m}$ approaches 1, and the tuning capacity C_t is substantially equal to the capacity of the tuning condenser C_o . Since an important application of the invention is to arrangements in which the input tuning condenser C_o is one unit of a gang of condensers operated by a single control, it is important to have the product $L_o \cdot C_t$ "track" or remain in alignment with the "L—C" products of the other tuned circuits, so that all of the tuned circuits tune to resonance together and it will be seen that this is

what occurs if $\frac{C_o}{C_m} \ll 1$, (i. e. is negligible in comparison with 1) for example at short wavelengths. At the same time, at short wavelengths the voltage, e , between antenna and ground, when the antenna is employed, is applied to the tuned circuit $L_o - C_o - C_m$ by means of the coupling between the circuit and the antenna through the capacity C_m . C_m being fixed, this coupling decreases at short wavelengths, and increases at long wavelengths. As a result of this arrangement, the wavelength characteristic of the input system employing an antenna is of more desirable form than has been hitherto obtainable, and by proper proportioning of the constants of this circuit, the wavelength characteristic may be made uniform or substantially constant over the wavelength range for which the system is designed. It therefore follows that the character of the performance of the receiving set is not substantially altered when the antenna is employed to supplement the loop, and that the signal energy applied to the radio frequency amplifier is approximately uniformly augmented over the wavelength range.

In addition to the advantages already described as resulting from an input system according to the present invention, the following advantages may be mentioned:—The amount of trimming which is required is very small compared with that which is frequently necessary with other arrangements, and

130

this results in extreme ease in tuning to different wavelengths, and in picking up different broadcast stations with a radio receiving set embodying the arrangement.

5 When the volume control is changed the resultant detuning of the system is very small. It is an easy matter to accommodate the system to different types and sizes of antennas which may be employed to supplement the loop. At short wavelengths the coupling of the input system to an antenna is weak, which is desirable, as pointed out above, since excessive amplifications are not required at short wavelengths. Moreover, the selectivity 10 of the system is high at short wavelengths, where an ordinary radio frequency amplifier is ordinarily relatively nonselective.

Other advantages of an input system according to the present invention will have 20 appeared from the foregoing description, and the invention is not limited to the particular arrangements or constants herein shown or described, but extends to many variations and modifications thereof, and is limited only by 25 the teachings of the foregoing specification, by the prior art, and by the following claims.

We claim:

1. An input-collector system for a radio frequency amplifier comprising, in combination, a series circuit including an inductance, 30 a coupling condenser connected to ground, a tuning condenser, an electromagnetic collecting device, and means for connecting a supplementary electrostatic collecting device 35 across said coupling condenser.

2. An input-collector system for a radio frequency amplifier, comprising a series circuit including an inductance susceptible of a trimming variation, a fixed coupling condenser connected to ground, a variable tuning condenser, and an electromagnetic collecting device; and means for optionally connecting 40 an electrostatic collecting device to said series circuit in such a manner as to supplement said electromagnetic collecting device, said coupling condenser having a capacity of 45 an order higher than that of the maximum capacity of the said tuning condenser.

3. An input-collector system for a radio 50 frequency amplifier, comprising a series circuit including an inductance susceptible of a trimming variation, a fixed coupling condenser connected to ground, a variable tuning condenser, and an electromagnetic collecting 55 device; and an electrostatic collecting device arranged for optional connection to said series circuit in such a manner as to supplement 60 said electromagnetic collecting device, said coupling condenser having a capacity of an order higher than that of the maximum 65 capacity of the said tuning condenser.

4. An input-collector system for a radio 65 frequency amplifier, comprising a series circuit including a trimmable inductance, a fixed 70 coupling condenser, a variable tuning con-

denser, an electromagnetic collecting device, and means for the optional connection to said circuit and across said coupling condenser of a supplementary electrostatic collecting device; and a volume control potentiometer 75 connected across said tuning condenser to permit variation of the potential applied from said input-collector system to a radio frequency amplifier with which said system is associated whether said potential be derived from said electromagnetic collector alone or from said electromagnetic and electrostatic collectors in combination.

5. An input-collector system for a radio frequency amplifier comprising, in combination, a trimmable inductance, a fixed coupling condenser connected to ground, an electromagnetic collecting device, means for the optional connection to said circuit of an electrostatic collecting device, a variable tuning condenser, and a potentiometer connected across said tuning condenser and provided with a variable tap adapted for connection to the grid of the first tube of a radio frequency amplifier.

6. A radio frequency receiving system comprising, in combination, a multi-stage radio frequency amplifier, an input-collector system comprising a series circuit including a trimmable inductance, a fixed coupling condenser, an electromagnetic collecting device, and means for the optional connection to said circuit of a supplementary electrostatic collecting device; and volume control means for applying to said radio frequency amplifier a variable portion of the total potential in 95 said input-collector system whether said potential be derived from said electromagnetic collector alone or from said electromagnetic and electrostatic collectors in combination.

In testimony whereof, we affix our signatures.
